DESIGN FOR A SURGICAL INSTRUMENT FOR APPLYING CARBON DIOXIDE SNOW OR SIMILAR ARTICLE

William J. Behr, Jr., Bloomfield, N. J.

Application June 2, 1942, Serial No. 107,076

Term of patent 14 years

To all whom it may concern:

Be it known that I, William J. Behr, Jr., a citizen of the United States, residing in Bloomfield, in the county of Essex, in the State of New Jersey, have invented a new, original, and ornamental Design for a Surgical Instrument for Applying Carbon Dioxide Snow or Similar Article, of which the following is a specification, reference being had to the accompanying drawing, forming a part thereof.

The figure is a perspective view of a surgical instrument for applying carbon dioxide snow, embodying my new design.

The other side of the instrument, not shown, is substantially like the side shown.

I claim:

The ornamental design for a surgical instrument for applying carbon dioxide snow or similar article, substantially as shown and described.
